(57) **CLAIM**

The ornamental design for a floating sun shield, as shown and described.

DESCRIPTION

FIG. 1 is a perspective view of a floating sun shield of the claimed design;

FIG. 2 is a top view of the floating sun shield device of FIG. 1 of the claimed design;

FIG. 3 is a side view of the floating sun shield of FIG. 1 of the claimed design;

FIG. 4 is an end view of the floating sun shield of FIG. 1 of the claimed design; and,

FIG. 5 is a bottom view of the floating sun shield of FIG. 1 of the claimed design.

The broken lines shown in FIGS. 1-5 are for illustrative purposes only and form no part of the claimed design.
